[57] CLAIM

The ornamental design for a combined drafting pen holder and container, as shown and described.

DESCRIPTION

FIG. 1 is a perspective view of a combined drafting pen holder and container showing my new design, with the cover partially removed for clarity;

FIG. 2 is a top plan view thereof;

FIG. 3 is a right side elevational view thereof;

FIG. 4 is a rear elevational view thereof;

FIG. 5 is a bottom plan view thereof;

FIG. 6 is a left side elevational view thereof; and

FIG. 7 is a front elevational view thereof.
